ALPHEUS W. ALTORFER, OF PEORIA, ILLINOIS, ASSIGNOR TO ALTORFER BROS. COMPANY, OF EAST PEORIA, ILLINOIS, A CORPORATION OF ILLINOIS.

WASHING-MACHINE MECHANISM.

1,241,895.

Specification of Letters Patent.

Patented Oct. 2, 1917.

Application filed January 15, 1915. Serial No. 2,364.

To all whom it may concern:

Be it known that I, ALPHEUS W. ALTORFER, a citizen of the United States, a resident of Peoria, in the county of Peoria and 5 State of Illinois, have invented new and useful Improvements in Washing-Machine Mechanism, of which the following is a specification.

This invention has reference to improvements in washing machines and particularly to the wringer mechanism, the mounting therefor and means for operating the same.

The object which I have in view is to mount the wringer so that it may be moved 15 relatively to the washing machine, with which it is associated, locked in its adjusted positions and power operated in any of its positions, and reversed if desired.

That the invention may be more fully understood, reference is had to the accompanying drawings, in which:

Figure 1 is a detail, showing in elevation and partly in section, the mounting for the wringer, locking means, and means for operating the wringer rolls in reverse directions;

Fig. 2 is a greatly reduced plan view of a washing machine support, partly broken away, also showing in plan and in section, the mounting for the wringer, and driving 30 mechanism therefor;

Fig. 3 is a greatly reduced side elevation of the wringer, pivotal mounting therefor and controlling means for the reverse gearing, and

Fig. 4 is a cross-section in plan, as the same would appear if taken on the line A—A of Fig. 3.

Like characters of reference denote corresponding parts throughout the figure.

In washing machines of the type herein shown and described, the wringer is so mounted that it may be moved from a position opposite or adjacent the washing machine to a position opposite or adjacent one 40 or more rinse tubs or other receptacles.

When the wringer is registering with the washing machine, clothes may be passed, directly from the washing machine into a rinse water tub. To wring the clothes from 45 the rinse water tub into a second rinse water tub, bluing water or basket, the wringer is moved from its position adjacent the washing machine, to a position where it will register with the rinse water tub and a second 50 rinse water tub, bluing water tub or basket,

whereby the clothes may be wrung directly from one tub into the other, or basket. The mechanism for operating the wringer being such that the wringer may be operated simultaneously with the washing machine 60 or independently thereof and reversed, if desired. In this way after a batch of clothes has been washed in the washing machine and passed into the rinse water tub, while the attendant is wringing the clothes from 65 the rinse water tub into a second rinse water tub, bluing water tub or basket, the washing machine may be filled with a second batch of clothes and subjected to the washing operation.

I have shown my invention applied to a washing machine including a stand on which the washing machine is mounted, it being necessary to provide a suitable support or supports for the rinse water tub or tubs and 70 basket, or rest the same on the floor. I wish it understood that the invention might be also applied to a "stave-leg" machine, or to a machine of the "platform" type, being that type employing a platform adapted to 75 support the washing machine and one or more rinse tubs or other receptacles.

1 designates a platform supported by legs 2. These legs are formed by bending side rails 3, to which the platform 1 is 80 secured, and said legs are braced by cross-bars 4. The platform 1 forms a rest for a washing machine 5, shown in outline in dotted lines only, Fig. 2, and the wringer, to be described, and its mounting, are preferably located at one corner of said platform, as will be explained.

Beneath the platform 1 is arranged the mechanism for receiving and transmitting motion from an electric motor or other suitable source of power to the wringer, and also to the washing machine, although no claim is made in this application to the washing machine or actuating means therefor.

6 designates a frame secured to the rails 3 beneath the platform 1. Secured to this frame and preferably suspended therefrom is an electric motor 7, said motor having a driving pulley 8. 9 is a shaft journaled in 95 suitable bearings and carries a pulley wheel 10, said wheel 10 being connected by a belt 11 with the pulley 8 of the motor. On the shaft 9 is a sprocket pinion 12, and said pinion is connected by a sprocket chain 13 105 110

with a sprocket wheel 14 carried by a shaft 15. The shaft 15 is arranged for the transmission of power to the wringer from the motor 7 and may also be used for transmitting power from said motor to the washing machine. This latter operation may be accomplished through the pinion 16 on the inner end of the shaft 15 actuating a suitable connection, not shown.

10 The wringer comprises the frame 17 in which are journaled the wringer rolls 18 and 19, geared together in a suitable manner, not shown, whereby they always rotate in unison and toward each other. The roll 15 19 has a shaft extension 20.

21 designates a bracket to which the wringer frame 17 is secured and which supports the same, whereby the wringer may be swung to two or more different positions.

20 The bracket has a mediate horizontal bearing portion 22 through which the end of the shaft 20 extends, and in which it is journaled, and also the spaced vertically aligned bearings 23 and 24. The lower bearing 23

25 terminates in a depending sleeve 25 divided by an annular flange or plate 26, said flange or plate provided with a radial slot 27.

The bracket 21 is revolvably supported on a tubular standard 28, preferably located at 30 one corner of the platform 1, as shown, having a base-plate 29 secured to said platform. The sleeve 25 of the bracket 21 extends down into and has a bearing in said standard 28, and the flange or plate 26 of the bracket rests upon and has a bearing on an annular flange or plate 30, similar in construction to the flange or plate 26, and said flange or plate 30 is provided with a plurality of radially arranged slots 31.

40 Pivoted at 32 to the bracket 21 is a lever 33. This lever has a hand gripping portion 34 and a locking end 35. Said locking end is adapted to enter the slot 27 in the flange or plate 26 and any one of the slots 31 in the plate or flange 30, when the bracket and wringer are swung, bringing the slot 27 of the plate or flange 26 coincident with one or the other of said slots 31 in the flange or plate 30. To remove the locking end 35 of

50 the lever from the slot 27 and also a slot 31 in the flange or plate 30, the attendant will swing the lever away from the wringer frame 17, which will release said locking end 35, causing it to bear against the peripheral face of the flange or plate 30 on which it will ride until the slot 27 in the plate or flange 26 is brought coincident with a slot 31 in the flange or plate 30, when the locking end 35 will enter said slots to lock

60 the wringer in such adjusted position. A spring 36 yieldingly holds the locking end 35 of lever against the peripheral face of the flange or plate 30 when the wringer is being swung from one position to another 65 and tends to force the locking end 35 into

slots 27 and 31, in manner described, when they are brought coincident. The spring 36 bears between a lug 37 on the locking end 35 of the lever and a lug 38 on the bracket 31.

39 denotes a shaft passing up through 70 the platform 1, the standard 28, the sleeve 25 of the bracket and through the aligned bearings 23 and 24 of said bracket, in which the upper end of the shaft is journaled.

Loosely carried on the shaft 39 between 75 the bearings 23 and 24, are bevel gear wheels 40 and 41, each having a clutch sleeve 42, and located on said shaft 39 between said gear wheels 40 and 41 and having a spline and groove connection with said shaft, whereby it may be moved longitudinally of the shaft, is a clutch sleeve 43 having clutch faces 44 to adapt the clutch sleeve 43 to be alternately brought into clutch engaging relation with said gear 80 wheels 40 and 41. And 45 is a bevel gear wheel on the outer end of the shaft extension 20 of the wringer roll 19, and said gear wheel 45 is in constant meshing relation with said bevel gear wheels 40 and 41, as 90 shown.

Thus it will be seen that when the shaft 39 is operated, it will rotate the clutch sleeve 43 and by moving said clutch sleeve into clutch relation with the bevel gear wheel 95 40, said gear wheel 40 will operate the bevel gear wheel 45 to rotate the wringer rolls in one direction, and when said clutch sleeve 43 is moved into clutch relation with the bevel gear wheel 41, said gear wheel 41 100 will operate the bevel gear wheel 45 to rotate the wringer rolls in an opposite direction.

To shift the clutch sleeve 43, I provide a yoke 46, see Fig. 4, which engages the sleeve 43, and said yoke is carried by a movable bar 47. Said bar at its upper end being suitably connected to the forward end of a lever 48, pivoted at 49 to an ear 50 of the bracket 21. The lever 48 extends alongside 110 of the wringer frame 17 and its free end is associated in a suitable way with a suitable catch 51, whereby the lever may be held in adjusted positions, up or down, or in a position which will hold the clutch sleeve 43 neutral between the bevel gear wheels 40 and 41.

A casing, forming a closure for the bevel gear wheels 40, 41 and 43, comprises sections 52 placed upon opposite sides of the bracket 21 and secured to ears 53 on said bracket, see Fig. 3. One of said sections 52 being slotted as at 54 to permit passage of an extension from the yoke 46, see Fig. 4, for an up and down movement therein when the yoke 46 is moved to clutch the sleeve 43 to either the bevel gear wheel 40 or the bevel gear wheel 41.

The shaft 39 is driven direct from the shaft 15. On the lower end of the shaft 39 130

is carried a bevel gear wheel 55 which is in constant meshing relation with a bevel gear wheel 56 on the outer end of said shaft 15, see Fig. 1. The shafts 39 and 15 at their 5 geared ends are preferably journaled in a bracket 57 having bearing portions 58 and 59, and said bracket is constructed in a manner to form a suitable guard for said bevel gears 55 and 56.

10 In Fig. 2 the washing machine is shown in outline, in dotted lines, and the wringer is also shown in outline, in dotted lines, in a position adjacent the washing machine, and when in such position clothes taken from the 15 machine may be passed directly through the wringer, and dropped into a rinse water tub positioned alongside the platform to receive such clothes, the rolls of the wringer having been first placed in operation by the attendant shifting the lever 48 to place the 20 sleeve 43 in clutch engagement with the proper gear on the upright shaft 39. To transfer the clothes from the rinse water tub into a bluing water tub, basket or other receptacle and to wring the same during such transfer, the wringer is swung around to the right, looking at Fig. 2, to a position at right angles to that shown, placing the same alongside the rinse water tub and between 25 it and the bluing water tub, basket or other receptacle, when the wringer may be again placed in operation and the clothes passed therethrough from one tub to the other, or into a basket or other receptacle.

30 With the arrangement shown, when clothes are being passed through the wringer to transfer such clothes from one tub into another, or into a basket or other receptacle, the washing machine may be again filled 35 with clothes and the washing operation going on during such wringing operation. The driving connections for the wringer are such that the wringer may be swung from one position to another while maintaining 40 the driving connection to said wringer.

45 While I have described the wringer as adapted to be moved to two different positions, I wish it understood that it may also be moved to a further position, or diametrically opposed to that position shown in Fig. 2, whereby the machine will accommodate one washing machine and three tubs, or two tubs and a basket or other receptacles.

50 What I claim is:

55 1. In a machine of the character described, in combination, a supporting frame, a tubular standard uprising from said frame and at its upper end provided with an annular plate or flange having a plurality of radial slots, a bracket revolvably mounted at the upper end of said standard and having a sleeve journaled in the upper end of the standard and also provided with an annular plate or flange resting on the annular plate or flange of the standard, said plate or flange of the standard, said plate

or flange of the bracket provided with a radial slot adapted to be brought coincident with either of the slots in the plate or flange of the standard, means adapted to enter the slot in the plate or flange of the bracket, 70 and either of said slots in the plate or flange of the standard for locking the bracket of the standard when swung to adjusted positions, a frame secured to said bracket, mechanism carried by said frame including an extension shaft journaled in said bracket, 75 an operating shaft extending up through the standard and also the sleeve of the bracket, clutch controlled gearing between the operating shaft and said extension shaft, 80 means for controlling the clutch, and means for operating said operating shaft.

2. In a machine of the character described, in combination, a supporting frame, a tubular standard uprising from said frame, a bracket revolvably mounted at the upper end of said standard, and provided with spaced bearing portions in axial alignment with the standard and with a transverse bearing portion, means for locking the bracket on the standard in a plurality of adjusted positions, a frame secured to said bracket, mechanism carried by said frame including a shaft journaled in the transverse bearing portion of said bracket, an operating shaft extending up through the standard and said spaced bearing portions of the bracket in axial alignment therewith, a pair of bevel gears loosely carried on the upper end of the operating shaft and a bevel gear on the shaft forming a part of the mechanism carried by said swinging frame and meshing with the gears on the operating shaft, a clutch sleeve feathered on the operating shaft and adapted to have a clutch engagement with either of the bevel gears carried thereon, whereby a reverse movement may be transmitted from the operating shaft to the mechanism on the frame, a lever for controlling said clutch sleeve, and means for operating said operating shaft.

3. In a machine of the character described, in combination, a supporting frame, a tubular standard uprising from said frame and at its upper end provided with an annular plate or flange having a plurality of radial slots, a bracket revolvably mounted at the upper end of said standard and having a sleeve journaled in the upper end of the standard and also provided with an annular plate or flange resting on the annular plate or flange of the standard, said plate or flange of the bracket provided with a radial slot adapted to be brought coincident with either of the slots in the plate or flange of the standard, a lever fulcrumed on the bracket, and swingable therewith and having a locking end adapted to enter the slot in the plate or flange of said bracket 125 130

- and either of said slots in the plate or flange of the standard for locking said bracket on the standard when swung to adjusted positions, a spring yieldingly holding the 5 locking end of the lever in operative position, a frame secured to said bracket, mechanism carried by said frame including a shaft extension journaled in said bracket, an operating shaft extending up through 10 the standard and the sleeve of the bracket, clutch controlled gearing between the operating shaft and said shaft extension, means for controlling the clutch, and means for operating said operating shaft.
- 15 4. In a machine of the character described, in combination, a supporting frame, a tubular standard uprising from said frame, a bracket revolvably mounted at the upper end of said standard and provided 20 with spaced bearing portions in axial alignment with the standard and with the transverse bearing portion, yielding locking means on the bracket for locking the same in a plurality of positions, a frame secured 25 to said bracket, mechanism carried by said frame including a shaft journaled in a transverse bearing portion on said bracket, an operating shaft extending up through the standard and said spaced bearing portions 30 of the bracket in axial alignment therewith, a pair of bevel gears loosely carried on the upper end of the operating shaft, a bevel gear on the shaft forming a part of the mechanism carried by said swinging frame 35 and meshing with said bevel gears on the operating shaft, a clutch member feathered on the operating shaft and adapted to have a clutch engagement with either of said gears carried thereon, whereby a reverse 40 movement may be transmitted from the operating shaft to the mechanism on the frame, a lever for controlling said clutch, a closure for said reverse gearing, and means for operating said operating shaft.
- 45 5. In a machine of the character described, in combination, a supporting frame, a tubular standard uprising from said frame, a bracket revolvably mounted at the upper end of said standard and having a 50 depending sleeve journaled in said standard, means for locking the bracket on the standard when swung to adjusted positions, a frame secured to said bracket, mechanism carried by said frame including an extension 55 shaft journaled in said bracket, an operat-
- ing shaft extending up through the depending sleeve in said bracket, a pair of spaced bevel gears loosely carried on the upper end of said operating shaft, a bevel gear on the outer end of the extension shaft meshing 60 with said gears on the operating shaft, a clutch member slidably secured to the operating shaft and adapted to be moved into clutch engagement with either of said bevel gears on said operating shaft, a yoke engaging the clutch member, a bar connected with said yoke, a lever pivotally connected with said bracket and connected with said bar, means for locking the lever in adjusted 65 positions, and means for transmitting motion from a suitable source of power to said operating shaft.
6. In a machine of the character described, in combination, a supporting frame, a tubular standard uprising from said frame, a bracket revolvably mounted at the upper end of said standard, said bracket and standard being provided with annular flanges, the former resting upon the latter, one of 75 said flanges being provided with a single radial slot and the other being provided with a plurality of radial slots, a frame secured to said bracket, and a lever having a locking part movable radially relatively to the axis of said standard and adapted to 80 enter the slots of said flanges for locking the bracket in adjusted positions on said standard.
7. In a machine of the character described, in combination, a supporting frame, 90 a tubular standard uprising from said frame, a bracket revolvably mounted at the upper end of said standard and having a depending sleeve forming a bearing in said standard, a locking member pivotally connected with the bracket and revolvably therewith, the bracket and standard adapted to be engaged by the locking member for locking the bracket in adjusted positions on said standard, a frame secured to the bracket, operating means on said frame, an operating shaft extending up through the standard and bearings formed on the bracket, means for operating said operating means from 95 said shaft, and means for actuating said 100 shaft.

ALPHEUS W. ALTORFER.
